UNITED STATES PATENT OFFICE.

ROBERT E. POWERS, OF NEW YORK, N. Y., ASSIGNOR OF ONE-HALF TO JOHN H. ALLEN,
OF NEW YORK, N. Y.

CAR-COUPING.

1,236,759.

Specification of Letters Patent. Patented Aug. 14, 1917.

Application filed February 29, 1916. Serial No. 81,114.

To all whom it may concern:

Be it known that I, ROBERT E. POWERS, a citizen of the United States, and resident of New York, county of New York, and State of New York, have invented an Improvement in Car-Couplings, of which the following is a specification.

The object of my invention is to provide manual means for operating a car coupler from the side of the car, and more particularly to provide capacity for centering the coupler into operative coupling position, whereby the couplers of cars to be connected may be brought into coupling alignment without the necessity of the operator becoming exposed to danger by entering between the cars to be coupled.

My invention consists of an adjustable mall which loosely fits over the coupler, and combining therewith means for operating the mall transversely, comprising a sliding bar suitably supported upon the car frame and preferably adapted to have rotary motion by which it may also be employed for operating the coupler pin, the construction being such that the operative relation of the device with the coupler pin is not affected by the lateral adjustment of the mall and its operative shaft. More specifically, my invention consists of a shaft held in supports on the car frame so as to have capacity for longitudinal adjustments, and having at its end adjacent to the central portion of the end of the car a mall-shaped structure suitably supported thereon and having a downwardly extending jaw engaging the coupler, said mall being connected with the shiftable shaft so as to move with it when shifted longitudinally, and thereby cause the coupler which the mall engages to be similarly shifted in a lateral direction in respect to the car frame.

My invention also comprehends details of construction which, with the features above stated, will be better understood by reference to the drawings, in which:—

Figure 1 is a plan view of a car coupler device embodying my improvements; Fig. 2 is a front elevation of the same with a portion of the coupler broken away; and Fig. 3 is a longitudinal sectional elevation on line $\alpha-\alpha$ of Fig. 2, but showing the coupler in full lines.

2 is the car frame or body; and 3 is the coupler and is connected with the car frame

in any suitable and well known manner. The coupler 3 is supported upon a transverse bar 17 which is secured in position by suitable castings or yokes which are bolted to the car frame in the well known manner. 60 The coupler 3 is so supported that it has freedom of lateral motion. 4 is a shaft arranged at the end of the car frame and is supported horizontally in suitable guide bearings 5 so as to have rotary as well as 65 longitudinal motion in said bearings. This shaft 4 extends from the central portion of the car above the coupler to or near the side of the car frame and may be provided with a laterally extending handle 6 by which it 70 may be operated, said handle normally extending downwardly. 13 is a cast metal mall having the jaw portion 14 which fits down and over the shank of the coupler 3. The upper end of this mall is provided with a 75 slotted journal bearing 15 which receives the end 7 of the shaft 4. The mall is retained in position upon the shaft by the cotter pin 16 which extends through the lateral flanges of the bearing, as will be clearly understood 80 by reference to Fig. 3. The mall is adjustably secured to the shaft 4 so that the shaft may rotate upon it but so as to cause the mall to be moved with any longitudinal adjustment of the shaft. In this manner, any 85 longitudinal adjustment of the shaft 4 will cause the coupler 3 to be adjusted through its engagement with the mall 13, and in this way the coupler may be shifted into the proper position of adjustment to enable the 90 proper coupling with another car. As shown in Fig. 3, the mall 13 is located between the yoke plate 18 which comes next to the car frame and the outer yoke plate 19 which is secured to the bottom plate 17. 95 In this way the mall is shielded and held in proper position longitudinally of the car but free to shift laterally between the yokes 18 and 19.

The shaft 4 is preferably provided with 100 a laterally extending arm 8 looped at the end as at 11. Hinged upon the looped portion 11 is a hinged arm 9, said arm being connected with the loop 11 by a looped portion 10. The arm 9 is approximately parallel with the shaft 4 but the connection between the loops 10 and 11 provides a hinged joint which gives the arm 9 considerable freedom though causing it to rise when the shaft 4 is rocked in its bearings. 110

12 is the pin of the coupler and is connected by any suitable loop or link with the arm 9 so that when the said arm is raised by the rocking of the shaft 4, the pin 12 is also raised and vice versa. In this manner, the mall shifting shaft is also adapted for raising and lowering the arm 9 for operating the coupler pin and permitting the said operation without shifting the mall, and similarly the mall may be shifted laterally of the car for positioning the coupler without operating the coupler pin, as there is freedom of movement between the arm 9 and the pin connections which will permit the arm 9 sliding through the link or loop of the pin. By the mechanism shown, a rocking motion of the shaft 4 operates the coupler pin, and a longitudinal shifting motion of the shaft 4 operates the mall for centering the coupler.

I do not restrict myself to the use of means for operating the coupler pin of the coupler, as the shaft 4 may be employed solely for operating the mall, but I prefer that the same shaft shall also have rocking capacity and provided with means for operating the coupler pin. Also, while I have shown a particular construction whereby the coupler pin may be operated, I do not in any way wish to be restricted to the particular connecting means shown, as any other suitable means may be employed whereby the rocking motion of the shaft may be utilized for operating the coupler pin, and therefore the mechanism shown may be taken by way of example and not as restriction.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details, as the same are susceptible of modification in various particulars without departing from the spirit or scope of the invention.

Having now described my invention, what I claim as new and desire to secure by Letters Patent, is:—

1. The combination of a car and coupler supported thereon so as to have capacity for lateral adjustment on the car, a transverse shaft journaled to the car with provision for endwise movement, means operable by a rocking motion of the shaft for operating the coupler pin, and means independent of the operating means loosely supported by the shaft to permit it to independently rock said means engaging the coupler whereby a longitudinal adjustment of the shaft will transversely adjust the coupler for positioning it.

2. The combination of a car and coupler supported thereon so as to have capacity for lateral adjustment on the car, a transverse shaft journaled to the car with provision for endwise movement, means operable by a rocking motion of the shaft for operating the coupler pin, and means connected with the shaft and engaging the coupler whereby a longitudinal adjustment of the shaft will transversely adjust the coupler for positioning it, said means consisting of a mall journaled upon the shaft but held thereto against independent motion longitudinally thereof and having a downwardly extending jaw portion which straddles the coupler.

3. The combination of a car and coupler supported thereon so as to have capacity for lateral adjustment, a shaft supported upon the end of the car with provision for longitudinal movement transversely of the length of the car, means extending downwardly from the shaft and movable therewith said means having a loose connection with the coupler whereby a longitudinal shifting of the shaft may adjust the coupler laterally, a coupler pin, and means for raising and lowering the pin carried by the shaft and operated by a rotary movement thereof.

4. The combination of a car and coupler supported thereon so as to have capacity for lateral adjustment, a shaft supported upon the end of the car with provision for longitudinal movement transversely of the length of the car, and means loosely journaled upon and extending downwardly from the shaft and movable longitudinally therewith said means consisting of a downwardly extending mall provided with a jaw on its lower part straddling the coupler and maintained in operative relation therewith by gravity, and fixed guides to prevent the mall from swinging clear of the coupling, the construction being such that a longitudinal adjustment of the shaft will cause the coupler to be adjusted laterally in respect to the car.

5. The combination of a car and a coupler supported thereon so as to have capacity for lateral adjustment, a transverse shaft arranged at the end of the car with provision for longitudinal adjustment, a mall having a jaw at its lower part extending over and receiving the coupler and having its upper part formed with a socket forming a detachable connection with the transverse shaft, and a pin extending across the socket for locking the mall to the shaft.

6. The combination of a car and coupler supported thereby so as to have capacity for lateral adjustment, a transverse shaft movable longitudinally with its inner end reaching adjacent to the coupler, loose connecting means between the shaft and the coupler

permitting normal movement of the coupler lengthwise of the car but maintaining connection with the shaft whereby a longitudinal movement of the shaft will adjust the 5 coupler laterally in respect to the car, coupler pin, and laterally extending means from the transverse shaft to maintain connection with the coupler pin during a longitudinal movement of the shaft and to op-

erate the pin by rotary movement of the 10 shaft.

In testimony of which invention, I hereunto set my hand.

ROBERT E. POWERS.
